UNITED STATES PATENT OFFICE.

McCLINTOCK YOUNG, JR., OF FREDERICK, MARYLAND.

HEEL-SPUR.

Specification of Letters Patent No. 27,019, dated January 31, 1860.

To all whom it may concern:

Be it known that I, MCCLINTOCK YOUNG, Jr., of the city and county of Frederick and State of Maryland, have invented a new and 5 Improved Equestrian Heel-Spur; and I do hereby declare that the following is a full and exact description thereof, reference being had to the accompanying drawings, which form a part of this specification, in 10 which—

Figure 1, is a top view of said spur, and Fig. 2, is a section thereof in the line y, y , of Fig. 1.

The main portion a , of the frame of my 15 improved heel-spur is of such a form that it will freely pass on to the heel of a boot or shoe; and the upwardly inclining hollow arm b , which projects from the curved side of said spur-frame, is of such a shape that 20 it will receive the screw-shank d , of the slit-headed head k , which receives within its slit the toothed spur-head e , that is combined therewith by means of a transverse pivot-pin.

The inner surface of the straight side of 25 the spur-frame a , is armed with sharp teeth h, h , and the inner end of the screw-shank d , is brought to a sharp point, as shown in the drawings; consequently, when my improved spur is placed upon the heel of a boot or 30 shoe, a few turns of the screw-shank d , will force the said points into the front and back sides of said heel, and securely hold the spur upon the same.

The nut f , which is placed upon the screw-shank d , enables the said shank to be securely retained in its position, after its point has been screwed into the heel of a boot or 35 shoe with the proper degree of force.

The loop c , on the upper side of the arm b , of the spur-frame, is intended to receive a 40 thong g , or any other suitable string or cord, which may be secured around the ankle of the person wearing the spur, as an additional security against losing the same, when the spur may be subjected to unusually rough 45 usage.

All danger of accidental separation of the screw-shank d , from the arm b , of the frame of the spur, may be prevented by passing a 50 pin i , through an aperture near the inner end of said screw-shank, as shown in Fig. 2.

What I claim as my invention and desire to secure by Letters Patent, is—

My improved equestrian heel-spur; the 55 said spur being formed essentially of the heel-shaped open frame a , and its projecting hollow arm b , combined with the slit-headed screw-shank d , and its rotating spur-head e , substantially as herein set forth.

The above specification of my improved 60 heel-spur, signed this 8th day of Decr. 1859.

MCCLINTOCK YOUNG, JR.
